EVAPORATIVE AIR-COOLER

Filed June 13, 1951

UNITED STATES PATENT OFFICE

2,681,217

EVAPORATIVE AIR-COOLER

Neal A. Pennington and Lawrence A. McKinney,
Tucson, Ariz., assignors of eleven-twentieths to
said Pennington, one-tenth to said McKinney,
one-tenth to Robert H. Henley, Tiptonville,
Tenn., and one-fourth to Roger Sherman Hear,
South Milwaukee, Wis.

Application June 13, 1951, Serial No. 231,394

5 Claims. (Cl. 261—98)

1

Our invention relates to new and useful improvements in evaporative air-coolers, and more particularly such coolers of the type in which air is adiabatically cooled by passing it through a foraminous pad, which is kept constantly wet with water.

Our invention is especially adapted for use in cooling the outgoing air in a summer air-conditioner of the type described and shown in U. S. Patent No. 2,464,766, issued March 15, 1949, to one of us, namely Neal A. Pennington; or for use in cooling the incoming air in a "desert cooler," so-called; or for use in cooling the incoming and/or outgoing air in a universal air-conditioner of the type described and shown in the copending application of said Pennington, Serial No. 765,554, filed August 1, 1947, and now abandoned, without prejudice to two continuations-in-part, Serial No. 234,301, filed June 29, 1951, and Serial No. 234,800, filed July 2, 1951.

In the past, the evaporative pad of such coolers has usually been of one of two sorts, namely: (1) a fixed pad through which water, pumped continuously to the top of the pad, seeps downwardly through the pad to a sump; or (2) a rotatable pad, each sector of which successively rotates through a tank of water and then across the air-stream.

It is the principal object of our present invention to devise a more efficient arrangement of pad and water-source, whereby the pad or pads, preferably (but not necessarily) horizontal athwart a vertical air-conduit, are supplied with water by means of a new and improved form of sprinkler.

It is a still further object of our invention to devise such sprinkler.

In addition to the objects just stated, we have worked out a number of novel and useful details, which will readily become evident as the following description progresses.

Our invention consists in the novel parts, and in the combination and arrangement thereof, which are defined in the appended claims, and of which one embodiment is exemplified in the accompanying drawings, which are hereinafter particularly described and explained.

Throughout the description the same reference number is applied to the same member or to similar members.

Figure 1 is a horizontal section of our air-cooler, looking downward along the lines 1—1 of Figure 2. Portions of both the upper and the lower pad are cut away, to expose what lies beneath them.

Figure 2 is a vertical section of our air-cooler, taken along the lines 2—2 of Figure 1.

2

Figure 3 is a vertical section of air-cooler, taken at right angles to the section of Figure 2, along the lines 3—3 of Figure 2.

Figure 4 is an enlarged side elevation of the sprinkler element as shown in Figure 3.

Figure 5 is an enlarged end elevation of said sprinkler, taken along the lines 5—5 of Figure 4.

Referring to the figures, and more particularly to Figures 2, 3, and 1, we see that 11 is the main casing of our invention.

Air enters at the bottom, through duct 12, into conduit 13. The top of conduit 13 is covered by a baffle 14, and above that there is a roof 15, each extending clear across the casing from front to rear as seen in Figure 2. Above the center of the roof there is a sprinkler 16, which will be more particularly described later herein.

It will be noted that roof 15 and baffle 14 beneath it constitute a centrally-located bridge 20 which extends clear across conduit 13 from front to rear, thus dividing the air-stream into two parts as the air passes through pad 17. This momentary division of the air-stream into two streams serves to get it past sprinkler 16 with the least impedance, and is the most convenient way to build the roof and baffle.

From each edge of the bridge there extends horizontally sidewise to the side of casing 11, and completely closing half of the air-passage 18, a half-pad 17. Air-passage 18 will be treated in the claims as a mere widened extension of conduit 13.

Louvres 19 in the sides of the upper portion of conduit 13, permit the escape of the divided air-stream into the two halves of passage 18, beneath the two halves of lower pad 17.

Above the sprinkler, and extending horizontally clear across passage 18, there is a second, or upper, pad 20. This upper pad is only about half or less as thick as the lower pad.

It will be noted that the bridge serves as a convenient central support for the very heavy lower pad 17.

The sides of casing 11 slope downwardly inwardly at 21, to form a sump 22.

A water supply-pipe 23, from some convenient source (not shown) enters the sump at one side, zigzags through the sump, passes to the sump at the other side, zigzags through it, and then passes upwardly to the sprinkler 16 which will now be described by reference to Figures 4 and 5. The object of these zigzags will be explained later herein.

A bracket 24, fastened to the rear wall of casing 11, extends horizontally to the middle of air-passage 18. The details of the sprinkler will now

be described. See Figures 4 and 5. A circular assemblage of slanted blades 25 is built integral with vertical axle 26, which is journaled in bracket 24 near the end of the latter. Near the top of axle 26, and integral therewith, is a stop 27 above bracket 24, to keep the axle from sliding downward out of its journal in the bracket.

The top of axle 26 is preferably pointed. Above this point is a fixed stop 28, mounted on bracket 24. Preferably this fixed stop is resiliently mounted as by being a leaf-spring.

Bracket 24 also supports pipe 23. Pipe 23 ends in two nozzles 29, each approximately below half way out from the center to the circumference of the assemblage of blades, and each so directed as to discharge a stream of water in a vertical plane at right angles to pipe 23, upwardly and sidewardly at an inclination of approximately 45 degrees against the blades.

At the top of passage 18 there is a fan 30, which sucks air up through the passage and discharges it into duct 31.

Drain-pipe 32 maintains the proper water-level in sump 22.

The operation of our invention is as follows.

Water, passing through the zigzags of supply-pipe 23 in sump 22 is pre-cooled by the evaporatively-cooled water in the sump, to nearly the wet-bulb temperature of the air. The thus pre-cooled water then passes on through pipe 23 to sprinkler 16.

The sprinkler, when at rest, hangs down, supported by stop 27 resting against the top of the end of bracket 24. When the two jets from nozzle 29 impinge upon the blades 25, axle 26 is forced upwardly thereby until the point of the axle bears against the lower face of the end of spring stop 28. This contact affords an excellent bearing for the rotation of the assemblage of blades.

The two jets of water cause the assemblage to rotate, and the rotating of the assemblage causes the water to spray out in all directions.

Part of this spray, plus entrained water which this pad filters out of the air, keeps upper pad 20 thoroughly wet. Water dripping off the bottom face of upper pad 20, mixed with the rest of the spray, keeps lower pad 17 thoroughly wet. Roof 14 and louvres 19 keep water out of conduit 18.

Air is sucked by fan 30, upwardly through duct 12, conduit 13, louvres 19, lower pad 17, passage 18, upper pad 20, more of passage 18, fan 30 itself, and out through duct 31.

In passing through lower pad 17, upper pad 20, and the spray-filled space between the two pads, the air becomes thoroughly evaporatively cooled to practically its wet-bulb temperature, and thereby the water itself, which drips off the bottom of the lower pad, and then finds its way to sump 22, is cooled to almost this temperature, especially in the reverse air-flow variant which will be hereinafter mentioned.

Thus, as already explained earlier herein, this thus-cooled water precools other water flowing through the zigzags of pipe 23 on its way to sprinkler 16, so that the spray-water is almost down to the wet-bulb temperature of the air when it first touches the air. Thus we achieve regenerative cooling without recirculation of the water.

This cooler of ours has a slight disadvantage in that some slight entrainment of mist in the air may occur. But, in the first place, most of this entrained water is filtered out by the upper

pad, and anyway the disadvantage of whatever entrainment remains, is offset by our device's greater cooling efficiency, greater simplicity, lesser cost, and saving of water by evaporating nearly all the water supplied to it.

Our device, as described, is adapted to be used in the single air-stream of a "desert" cooler, and in outgoing air-stream of the Pennington patent or the Pennington application referred to near the beginning of this specification.

If it be desired to use our invention in the incoming air-stream of the Pennington application, for example, all that is necessary is to reverse air-fan 30 so as to force air downwardly, instead of sucking air upwardly. This is because it is advisable for the two air-streams to counter-flow through the rotary heat-transferer of the Pennington patent, and through both the rotary heat-transferer and the rotary moisture-transferer as the Pennington application.

Certain modifications are possible in our invention. For example, other forms of sprinkler could be substituted, the bridge could be built below the lower pad, instead of in it, the pads could be vertical and the air passages horizontal, and/or the upper pad could be omitted. But, by and large, we prefer not to make any of these changes.

Having now described one exemplification of our invention, we wish it to be understood that our invention is not to be limited to the specific form or arrangement of parts herein described and shown.

We claim:

1. In an evaporative cooler for air-conditioning, the combination of: a substantially vertical air conduit; two substantially parallel spaced substantially horizontal foraminous air-permeable pads athwart the conduit; a liquid sprinkler centrally located between the two pads, so as to wet both pads; a liquid supply-pipe, leading to the sprinkler; a sump extending across the conduit below the lower of the two pads; a constricted portion of the conduit, extending vertically through the middle of the sump, directly below the sprinkler; a downwardly outwardly inclined roof completely covering the constricted portion, to prevent the entrance of water into this constricted portion and to divert the water into the sump; and openings in the sides of this constricted portion beneath the edges of the roof, to permit the passage of air.

2. An evaporative cooler according to claim 1, further characterized by the fact that there is, below the room, an outwardly upwardly inclined baffle, extending substantially across the constricted portion of the conduit, to divert the upward flow of air sidewardly through the side openings.

3. An evaporative cooler according to claim 2, further characterized by the fact that the side openings are protected by outwardly downwardly inclined louvres.

4. An evaporative cooler, according to claim 1, further characterized by the fact that there is, below the roof, an outwardly upwardly inclined baffle, extending substantially across the constricted portion of the conduit, to divert the upward flow of air sidewardly through the side openings, and that the roof and the baffle together constitute a bridge, extending across the conduit, and serving to support the middle of the lower pad.

5. An evaporative cooler, according to claim 1, further characterized by the fact that the sprin-

kler comprises a substantially horizontal revolvable assemblage of slanted blades; a substantially vertical elongated axle, rigidly attached to the assemblage, and having a pointed upper end; a plurality of jets, located below the assemblage each jet being so inclined that the liquid therefrom will impinge on the faces of successive blades of the assemblage to cause it to rotate; bearings for the axle, in which bearings the axle is freely slideable axially; a stop associated with the axle to limit the downward sliding of the axle under the influence of gravity; and a flat leaf spring against the face of which near one end thereof the point only of the pointed end of the axle rests, when the assemblage is pushed upwardly by the action of the jets.
